UNITED STATES PATENT OFFICE.

NICHOLAS FISCHER, EDWARD J. FISCHER, AND PETER J. FISCHER, OF CINCINNATI, OHIO.

WEATHER-COVERING FOR BUILDINGS.

No. 838,015.

Specification of Letters Patent.

Patented Dec. 11, 1906.

Application filed April 23, 1906. Serial No. 313,136.

To all whom it may concern:

Be it known that we, NICHOLAS FISCHER, EDWARD J. FISCHER, and PETER J. FISCHER, citizens of the United States of America, and 5 residents of Cincinnati, county of Hamilton, State of Ohio, have invented certain new and useful Improvements in Weather-Covering for Buildings, of which the following is a specification.

10 Our invention relates to coverings for buildings which take the place of a weather-boarding.

The object of our invention is a covering of this kind made up of blocks and holding- 15 strips which interlock firmly and snugly one with the other, so as to form a firm vertical covering for the sides of buildings, and in which the blocks are of a strong construction and one which may be applied readily in the 20 course of construction of a building.

Referring to the accompanying drawings, in which like parts are indicated by similar reference-letters, Figure 1 is a perspective view of a part of a vertical wall of a building 25 supplied with a weather-covering embodying our invention. Fig. 2 is a vertical section of a part of the vertical wall of a building upon an enlarged scale. Fig. 3 is a perspective view of one of the blocks used in our weather- 30 covering upon a still more enlarged scale.

Referring to the parts, the walls of the building may consist of any of the ordinary constructions now in use, such as scantling *a*, covered with the ordinary boards *a'* which

35 are used to cover the framework of the building preparatory to receiving a weather-boarding. To this boarding *a'* we secure horizontal holding-strips *B* at regular intervals. These holding-strips *B* in cross-section are 40 made in the form of a trapezoid, the converging sides *b b'* being formed, preferably, at an angle of about sixty degrees to the broader parallel side *b²*. These holding-strips *B* are secured to the vertical boarding *a'* of the building with the narrow parallel side *b³* contacting the wall and are secured at a distance apart equal to the width of the covering-blocks *C*.

Blocks *C* are made, preferably, from earth- 50 enware, such as used in tile. They are made with parallel faces *c c'*. The inner face has formed in it a horizontal groove *c²* of a shape corresponding to the shape of the holding-

strip *B*. The upper edge *c³* and the lower edge *c⁴* of the block *C* are made, preferably, at 55 the same angle to the inner face *c* of the block as the lower edge *b'* of the holding-strip bears to the parallel faces of the strips. Similarly the wall *c⁵* of the groove *c²* in the block is made at an angle to the face *c* corresponding 60 to the angle at which the side *b* of the holding-strip is made to the parallel faces thereof. The notch *c²* is made of a depth equal to the depth of the holding-strip *B*, so that when the block *C* is in place a cross-section through 65 the block and the holding-strip presents the contour of a parallelogram.

The preferred form of applying the blocks to the wall is to secure a series of blocks in a horizontal line on a holding-strip and then to 70 place a series of blocks upon the adjacent holding-strip. When the blocks are so secured, it is seen that the walls *c⁵* of the groove *c²* take over the upper edges *b* of the holding-strip, the upper edge *c³* of the block takes under the lower edge *b'* of the holding-strip *B* next above the block, and that the lower edge *c⁴* of the block bears against and conforms to 75 the face *c³* of the block next below it. Thus the blocks are held firmly in a vertical position both by the holding-strips *B* and by the edges of the adjacent rows of blocks.

One end of the block *C* has a vertical notch *c⁶* cut in its under face, and the other end of the block has a similar notch *c⁷* cut in its upper face, so that when placed in position the ends of the blocks overlap each other.

What we claim is—

1. A weather-covering for buildings consisting of holding-strips in cross-section substantially the shape of a trapezoid, secured to the walls of a building, with the shorter faces adjacent to the wall, and rows of tiles having grooves in their inner faces fitting over the holding-strips, and having the upper edges of 90 a row of tiles to fit under the adjacent holding-strip and under the lower edge of the adjacent row of tiles.

2. A weather-covering for buildings consisting of holding-strips in cross-section of 100 the shape of a trapezoid to be secured horizontally to the walls of a building with the shorter parallel face adjacent to the walls, blocks with parallel inner and outer faces having grooves cut in the inner faces from 105 the lower edge, the upper wall of the groove

being made at an angle to the faces of the block corresponding to the angle which the upper angular edge of the holding-strip has to its parallel faces, and the upper and lower edges of the block being formed with angles corresponding to the lower edge of the holding-strip, the blocks being secured in place upon the holding-strips with their upper and lower edges contacting the corresponding

lower and upper edges of the adjacent rows of blocks.

NICHOLAS FISCHER.
